(57) **CLAIM**

The ornamental design for a tropical tree assembly for a patio table, as shown and described.

DESCRIPTION

FIG. 1 is a perspective view of a tropical tree assembly for a patio table, showing my new design, the table shown in broken lines for illustrative purposes only and forms no part of the claimed design;

FIG. 2 is a perspective view of the top part of the tree assembly of FIG. 1 in a closed position, shown separately for ease of illustration;

FIG. 3 is a perspective view of a second embodiment of FIG. 2, the trunk shown with a decorative cover;

FIG. 4 is a front elevational view of the support structure of FIG. 1, shown separately for ease of illustration, the rear being identical;

FIG. 5 is a top plan view of FIG. 4;

FIG. 6 is a side elevational view of FIG. 4, the opposite side substantially the same;

FIG. 7 is a bottom plan view of FIG. 4;

FIG. 8 is a front elevational view of a second embodiment of FIG. 4, the support structure having a sleeve cover, the rear being identical;

FIG. 9 is a top plan view of FIG. 8;

FIG. 10 is a side elevational view of FIG. 8, the opposite side being substantially the same;

FIG. 11 is a front elevational view of a third embodiment of FIG. 4, the support structure having a sleeve cover, the rear being identical;

FIG. 12 is a perspective view of a second embodiment of a FIG. 1, the table shown in broken lines for illustrative purposes only and forms no part of the claimed design;

FIG. 13 is a perspective view of the top part of the trunk of the tree assembly of FIG. 12, the branches removed for ease of illustration;

FIG. 14 is a top plan view of a branch of the tree assembly of FIG. 12, shown separately for ease of illustration;

FIG. 15 is a front elevational view of the support structure of FIG. 12, shown separately for ease of illustration, the rear being identical;

FIG. 16 is a side elevational view of FIG. 15, the opposite side being substantially similar;

FIG. 17 is a perspective view of a third embodiment of FIG. 1, the patio table shown in broken lines for illustrative purposes only and forms no part of the claimed design;

FIG. 18 is a perspective view of the top part of FIG. 17, the branches removed for ease of illustration;

FIG. 19 is a top plan view of a branch of FIG. 17 shown separately for ease of illustration;

FIG. 20 is a front elevational view of the support structure of FIG. 17, the trunk having a decorative sleeve cover, the rear being identical; and,

FIG. 21 is a side elevational view of FIG. 20, the opposite side being substantially similar.

The elements shown in broken lines are not parts of the design.
